[57] CLAIM

The ornamental design for a microform reader/viewer, or similar article, as shown and described.

DESCRIPTION

FIG. 1 is a right side elevational view of a Microform Reader/Viewer showing my new design in an open position.

FIG. 2 is a front elevational view thereof.

FIG. 3 is a top plan view thereof.

FIG. 4 is a rear elevational view of the design shown in FIG. 1.

FIG. 5 is a left side elevational view thereof.

FIG. 6 is a rear perspective view of the design shown in FIG. 1 in the closed position.

FIG. 7 is a bottom plan view thereof.

FIG. 8 is a front perspective view thereof.

FIG. 9 is a top front perspective view of the design in an open position.
